UNITED STATES PATENT OFFICE.

ARTHUR B. CHRISTOPHER, OF ST. LOUIS, MISSOURI, ASSIGNOR, BY MESNE ASSIGNMENTS, TO METALLIC INDUSTRIES, INC., A CORPORATION OF DELAWARE.

SWIVELING TEETER.

1,427,722.

Specification of Letters Patent. Patented Aug. 29, 1922.

Application filed February 14, 1920. Serial No. 358,563.

To all whom it may concern:

Be it known that I, ARTHUR B. CHRISTOPHER, a citizen of the United States, residing in the city of St. Louis and State of 5 Missouri, have invented new and useful Improvements in Swiveling Teeters, of which the following is a specification.

This invention relates to a teeter or see-saw, and the general object of the invention 10 is to produce a teeter of simple construction which will be strong and safe and which is so constructed that the upper frame can readily be folded. The base or support for the frame is also constructed so that it can 15 be readily taken apart so that the parts of the teeter can be packed in a small space. A further object of the invention is to improve the general construction of a teeter of this type and to provide improved means for 20 attaching the seats or saddles upon which the children sit. One of the purposes of the invention is to provide a construction which will be very inexpensive to manufacture.

Further objects of the invention will appear hereinafter.

The invention consists of the novel features, and in the general combination of parts to be particularly described hereinafter, all of which contribute to produce a 30 simple and safe teeter or see-saw. A preferred embodiment of my invention will be particularly described in the following specification, while the broad scope of my invention will be pointed out in the appended 35 claims.

In the drawing,

Figure 1 is a plan of a teeter embodying my invention;

Figure 2 is a side elevation;

40 Figure 3 is an end elevation;

Figure 3^a is a cross section taken about in the plane of the line 3—3 of Figure 2;

Figure 4 is a side elevation of the center plate which constitutes a feature of the 45 invention; and

Figure 5 is a side elevation of a base plate which supports the center plate.

The teeter comprises an upper frame 1, each side of which is formed of two side bars 50 2 and 3 with overlapping portions 4 at their middle points, the said overlapping portions being connected together by removable bolts 5. At the overlapping portions 4 one of the side bars is off-set so that the bodies of the 55 side bars are in substantially the same plane, giving the frame the same width throughout

the principal portion of its length. At each end the side bars have converging portions 6 which terminate in substantially parallel extensions 7. To the ends of the frame 1 saddles 8 are respectively attached. These saddles or seats are preferably attached to the extensions 7 and are preferably formed of pressed sheets from which integral ears 9 are struck downwardly, said ears being attached 60 by through bolts 10 to the extensions 7. The outer ends of the upper frame near the converging portions 6 are provided with cross braces 11, respectively, and opposite these cross braces upwardly extending bracket 65 plates 12 are provided which support transverse handles 13. These handles are within convenient reach of a child sitting upon the saddle or seat 8. Near the overlapping portions 4 the upper frame is provided with two 70 transverse cross bars 14 and these are connected by horizontal slats 15, the outer ends of which are attached to the converging portions 6. These slats 15 have their "flats" in a 75 horizontal plane.

In order to provide for giving the teeter frame a rocking movement, I provide the side bars of the frame with downwardly extending straps 16 each consisting of a short flat bar which is riveted to the outer bar of 80 the overlapping portion 4, but these rivets do not pass through both of the bars at the overlapping portions; the lower ends of these side straps 16 carry a transversely disposed bar forming a trunnion 17 which may consist of a tube, and in order to effectively 85 brace these straps I provide inclined braces 18 in the form of long flat bars. These braces have openings as in the strap 16, which receive the trunnion 17, and the outer ends of 90 the inclined braces 18 are attached at 18^a to the upper frame near the ends thereof, preferably at the location of the cross bars 11. With this construction it will be evident that by removing the bolts 5, the trunnion 17 95 can operate as a pivot on which the two ends of the upper frame could fold together, it being understood, that the upper frame would be first removed from its support.

In other words, the side bars 2 and 3 are 100 secured together by means of a disconnectible joint.

I shall now describe the means for supporting the upper frame so that it can rock, and also so that it can have a pivotal movement, if desired.

For this purpose I provide supporting

means including a base plate 19 which is in the form of a disc which is supported on suitable legs 20 by means of joint connections 21 between the legs and the base plate. 5 These legs 20 incline outwardly in a downward direction and are connected together by braces 23 and 24. These joints 21 are so constructed that the legs will be attached to the base plate by moving the same inwardly or toward the center of the base plate, and when so constructed, it will be evident that the braces 23 and 24 will operate to prevent the legs from becoming detached from the base plate at these joints. 10 15 To form the joints 21, I prefer to strike outwardly projecting tongues 22 from this plate. The legs 20 are preferably in the form of tubes or pipes, the bottoms of which are bent upwardly to form feet 25; the upper 20 ends of these legs form sleeves or sockets 26, and are bent horizontally and flattened out so as to enable them to be forced over the tongues 22. The braces 23 and 24 can be constructed in any suitable manner; however, I prefer that the brace 23 shall first 25 connect two of the legs and then the brace 24 connect the brace 23 with the intermediate leg. For this purpose the brace 24 may be provided with a notch 27 which engages a 30 corresponding notch in the brace 23 (see Fig. 3a).

On the base plate I prefer to provide a center plate 28 which is also of circular form, and this center plate carries brackets or ears 35 for supporting the trunnion 17. They are preferably formed as integral ears 29, bent upwardly from the edges of the disc or center plate 28. These ears are formed each with a notch 30 which receives the end of the 40 trunnion, (see Fig. 3).

In connection with the saddles or seats 8, it should be mentioned that it is important that the extensions 7 should project a considerable distance beyond the bolts 10 and 45 should engage the underside of the plate out of which the saddle or seat is formed. By giving these parts this relation, the projecting ends of the extensions 7 will prevent the saddle 8 from rotating in a rearward direction on the pivot bolt. In other words, the 50 plate forming the saddle rests on the frame at both sides of the bolt.

If desired, the center plate can be attached to the base plate 19 by means of a center bolt 55 31, or king bolt (see Fig. 3). If such a king bolt is used the children playing with the teeter can use it as a merry-go-round.

Evidently by removing the bolts 32 which attach the braces 23 and 24 to the legs 20, 60 the legs can readily be detached from the base plate 19. Furthermore, the upper frame may be lifted off of the center plate 28 and then folded in the manner described above so that the parts of the teeter may be packed 65 into a neat bundle for shipment.

It is understood that the embodiment of the invention described herein is only one of the many embodiments my invention may take, and I do not wish to be limited in the practice of my invention nor in my claims, 70 to the particular embodiment set forth.

What I claim and desire to secure by Letters Patent is:

1. In a teeter or see-saw, the combination of a center plate, means for supporting the 75 same in a substantially horizontal position, a substantially horizontal elongated upper frame comprising two separated bars, a substantially vertically disposed strap secured to each side bar and extending downwardly 80 therefrom, a bar forming a trunnion extending transversely of the upper frame, secured to said vertical straps, and ears projecting up from the center plate at opposite sides thereof and having sockets open on their 85 upper side, rotatably supporting the ends of said trunnion, said ears lying adjacent to the faces of said straps respectively and preventing lateral movement of the upper frame on the center plate. 90

2. In a teeter or see-saw, the combination of a center-plate, a base plate supporting said center-plate, means for supporting said base plate at an elevation above the floor, said center-plate having integral ears projecting upwardly therefrom, a substantially horizontal elongated upper-frame having side bars overlapping each other adjacent said center-plate, removable bolts for attaching the overlapping portions of said 100 side bars to each other, substantially vertically disposed side straps at the overlapping part thereof, and extending downwardly therefrom at each side of the upper-frame, carried by said side bars, and a trunnion carried by said side straps and rotatably supported by said ears. 105

3. In a teeter or see-saw, the combination of a center-plate, a base plate beneath said center-plate, means for supporting said base plate at an elevation above the floor, said center-plate having integral ears projecting upwardly therefrom, a substantially horizontal elongated upper-frame having side bars overlapping each other adjacent said center-plate, removable bolts for attaching the overlapping portions of said side bars to each other, substantially vertically disposed side straps at the overlapping part thereof, and extending downwardly therefrom at each side of the upper-frame, carried by said side straps, a trunnion extending transversely and rotatably supported by said ears, and inclined braces attached to said trunnion adjacent to said side straps and secured to the said upper-frame toward the ends thereof. 115 120 125

4. In a teeter or see-saw, the combination of a center-plate, a base plate beneath said center-plate, a plurality of legs having joint 130

connections with said base plate and removable from the base plate at said joints, said legs inclining outwardly in a downward direction, braces connecting said legs to prevent spreading thereof and to maintain their joint connections with the base plate, a substantially elongated upper-frame mounted to rock on said center-plate and having side bars overlapping each other adjacent the center-plate, removable bolts connecting the overlapping portions of the side bars, side straps extending downwardly from the side bars adjacent the center-plate, a trunnion carried thereby, and inclined braces attached to said trunnion and attached at their outer ends to the upper-frame.

5. In a teeter or see-saw, the combination of a center-plate, a base plate for supporting the same, said base plate having outwardly projecting tongues struck therefrom, legs having sockets in the form of sleeves at their upper ends receiving said tongues, braces connecting said legs and operating as the means for holding said sockets on said 20 tongues, said center-plate having upwardly extending integral ears, an upper-frame, and a transverse trunnion carried thereby and mounted to rock on said ears.

6. In a teeter or see-saw, the combination of a base plate having a plurality of tongues struck therefrom and projecting outwardly, a plurality of legs of tubular form, said legs having sleeves forming sockets at their upper ends receiving said tongues, braces connecting said legs, and preventing withdrawal of the tongues from the sockets, and an upper frame supported to rock upon said 35 base plate.

7. In a teeter or see-saw, the combination of a base plate, having a plurality of outwardly projecting tongues struck therefrom,

a plurality of legs having sockets at their upper ends receiving said tongues, braces connecting said legs, and preventing withdrawal of the tongues from the sockets, a 45 center-plate pivotally mounted on said plate and having upwardly projecting ears, and an upper-frame having a trunnion mounted to rock on said ears.

8. In a teeter or see-saw, an upper frame 50 having a disconnectible joint connection substantially at its middle point, rigid side straps extending downwardly from the joint connection, inclined brace bars secured toward the outer ends of the frame, with 55 their inclined ends disposed adjacent the side straps, and a trunnion in the form of a bar passing through the side straps and the braces, said trunnion acting as an axis of rotation to fold the frame when the joint 60 is disconnected.

9. In a teeter or see-saw, the combination of a pair of oppositely disposed substantially parallel side bars, a second pair of oppositely disposed substantially parallel side bars, a 65 transverse bar forming a rocking trunnion for the see-saw, inclined braces having aligning openings receiving the trunnion and rigidly secured to the side bars toward their outer ends, substantially vertical side straps 70 extending upwardly from the trunnion and connected with the aforesaid side bars for bracing the same, and removable means for connecting the first pair of bars to the second pair of bars and adapted to be removed 75 to permit one pair of bars to be folded over the other pair of bars by a rotation on the axis of the trunnion.

In testimony whereof, I have hereunto set my hand.

ARTHUR B. CHRISTOPHER.
